EDUCATIONAL GAME BOARD

Solomon Bernstein, 1367 Morrissey Blvd., Quincy, Mass.

Filed Apr. 8, 1963, Ser. No. 74,349

Term of patent 14 years

(Cl. D34—5)

The figure is a top plan view of an educational game board showing my design.

The game board is of conventional thickness. The dominant feature of my design resides in the portions shown in full lines.

I claim:

The ornamental design for an educational game board, substantially as shown and described.
